UNITED STATES PATENT OFFICE

2,584,358

ADJUSTING BUCKLE FOR THE SUSPENSION STRAPS LEADING FROM A PARACHUTE HARNESS TO THE PARACHUTE

Carl Herman Lundholm, Stockholm, Sweden

Application April 6, 1950, Serial No. 154,232

4 Claims. (Cl. 244—151)

1

The present invention relates to an improvement of the adjusting buckles which are arranged on the suspension straps leading from the parachute harness to the parachute proper, viz. on harnesses fitted with a quick release connector. Parachute harnesses with quick release connectors may be divided into two main categories, namely:

1. Such harnesses, which have two pairs of suspension straps leading from the harness to the 10 parachute, one pair being arranged on each side, one strap in each pair passing, in use, at the back of the wearer downwards under his seat where such straps together form a U-shaped sling, the other strap in each pair being, in use, releasably fastened to the quick release connector. Each pair of suspension straps is slidably interconnected by an adjusting buckle placed at the upper front of the wearer, which buckle hitherto usually has been of rectangular shape and has had one broad and one narrow slot. The former is adapted for receiving both suspension straps in a pair, the latter only the end which is to be releasably connected with the quick release connector.

2. Such harnesses, where both pairs of suspension straps are passed at either side of the back of the wearer downwards to his seat, where they each form a U-shaped sling, further one or two special straps, which are arranged at the upper front of the wearer for releasable connection with the quick release connector. This strap or straps may be either permanently or slidably connected with the suspension straps, in the latter case by an adjusting buckle.

Both the described categories of harnesses have their advantages and drawbacks.

The principal advantage of the former harness consists therein that the wearer on landing may get altogether free from the harness, after the strap ends engaged in the quick release connector are freed therefrom. The drawback consists therein that the wearer, after a jump, gets his head jammed between both pairs of suspension straps. Moreover the adjusting buckles have a tendency to slide upwards through the jerk arising at a jump, whereby an arrow-shaped gap is formed by each pair of said straps, which naturally makes the position of the parachutist still more uncomfortable.

The second harness type is more comfortable to the wearer at a jump, because the suspension straps get well removed from his head and are also well assembled in each pair by the adjusting buckles. The drawback with this type con-

sists therein that the wearer, after landing, does not get free from the harness at his shoulders, although the upper strap ends have been disengaged from the quick release connector. Therefore he has to take off the harness in the same way as one takes off a waist coat, which may be difficult, if he is dragged along the ground after an inflated parachute, or if he descends into water.

The object of the present invention is to propose a harness, which combines the advantages of both the harnesses described without having any of their drawbacks. For that purpose, a new type of adjusting buckle for the suspension straps is proposed for the first category of harness described.

The new buckle differs from those used hitherto both as regards transversely extending slots and the shape. Whilst in ordinary adjusting buckles, the ends of upper slots are situated right above corresponding ends of slots underneath, and the shape of such buckles mostly is substantially rectangular, a buckle, according to this invention has at least one upper slot the outwards directed end of which projects over the corresponding end of a slot arranged underneath the former. Further the shape of the new buckle is substantially a rhomboid. Preferably two upper broad slots are arranged for receiving both suspension straps on each side and two narrow slots with a breadth about half of that of the former slots for receiving only the strap which is adapted to be releasably fastened to the quick release connector. By this arrangement, the suspension straps will when the parachutist is suspended in the harness get well removed from the head. By the greater number of slots, any undesirable sliding upwards of the buckle on the harness being subjected to the load of the user is avoided.

Instead of consisting of one rhomboid only, the buckle can be made of two rhomboids, the upper one housing the broad slots and the lower one the narrow slots. The lower longitudinal side of the former portion is partly joined with the upper longitudinal side of the latter. By such a shape, the suspension straps may be still further removed from the head of the parachutist than if the buckle is only made up of one rhomboid. In any case, it is natural that the ends of the slots form substantially straight lines throughout the buckle. The number of slots may also vary depending on the webbing used in the harness. If the surface of the same is very smooth, it may thus be advisable to use more than four slots.

The invention is illustrated on the accompanying drawing.

Fig. 1 shows a harness embodying the new invention.

Fig. 2 is a plan view of a substantially rhomboid-shaped adjusting of buckle.

The various details in the harness are numbered as follows:

1 shows the upper portion of the suspension straps leading to the parachute (not shown), 11 the lower portions of the same passing under the seat of the wearer, 12 are the suspension straps which are releasably fastened to the quick release connector. 2 denotes the leg straps passing between the wearer's legs. 3 shows two straps arranged crosswise at the back. 4 is a waist strap, 5 and 6 are fastening straps for a ring-shaped member, which is designed to pull the leg straps to the sides. 8 shows the quick release connector. 10 is a substantially rhomboid shaped adjusting buckle for the suspension straps, which constitutes the principal feature of this invention. 11 and 12 are adjusting buckles for the leg straps and the waist straps respectively. 13 is a short horizontal strap passing below the neck of the wearer. 14 shows a handle for effecting the manual release of the parachute, whilst 15 is a cable from said handle to the parachute pack (not shown). 16 is a broad strap for the placement of the handle 14. 17 shows fastening means at the free strap ends of the suspension straps 12 and the leg straps 2 for engagement in the quick release connector. 25 are broad and 26 narrow slots in the rhomboid-shaped adjusting buckle 10, whilst 27 denotes the principal portion of the ring-shaped member and 27¹ the slots arranged therein.

Having now described my invention, what I claim as new and desire to secure by Letters Patent is:

1. Device on a parachute harness fitted with a quick release connector and two pairs of suspension straps leading from the harness to the parachute, one pair being arranged on each side, one strap in each pair being adapted to pass at the back of the wearer downwards under his seat such straps together form a U-shaped sling, the other strap in each pair being adapted to be releasably fastened to the quick release connector, both straps in each pair being slidably interconnected by an adjusting buckle, which, in use, is placed at the upper front of the wearer, said buckle having at least two transversely extending

slots, the one of which is arranged above the other, the upper slot being adapted to receive both suspension straps in a pair, the lower slot only the strap which is adapted for releasable engagement in the quick release connector, the outwards directed end of the upper slot projecting over the corresponding end of the lower slot, whereby the suspension straps, during a jump, are removed from the neighbourhood of the head of the parachutist.

2. Device according to claim 1 in which the adjusting buckle has the shape of substantially a rhomboid.

3. Device on a parachute harness with a quick release connector and two pairs of suspension straps leading from the harness to the parachute, one pair being arranged on each side, one strap in each pair being adapted to pass at the back of the wearer downwards under his seat where such straps together form a U-shaped sling, the other strap in each pair being adapted for releasable engagement in the quick release connector, both straps in each pair being slidably interconnected by an adjusting buckle, which, in use, is placed at the upper front of the wearer, said buckle having at least four transversely extending slots which are arranged one above another, the upper two of said slots being adapted to receive both straps in a pair, and the lower two slots only the strap which is adapted for releasable engagement in the quick release connector.

4. Device according to claim 3 having an adjusting buckle in which the upper two slots are substantially twice as broad as the lower two slots.
